ELECTRICAL CONTROL

Richard M. Somers, West Orange, and Charles T. Jacobs, New Providence, N. J., assignors to Thomas A. Edison, Incorporated, West Orange, N. J., a corporation of New Jersey

Application April 6, 1939, Serial No. 266,338

18 Claims. (Cl. 175—335)

This invention relates to electrical control, and more particularly to such control of the position of a movable system—which may be a system, itself of any nature, which it is desired to move selectively between a plurality of positions. An embodiment of the invention involves the mechanical association with the movable system of electrically actuatable moving means—typically electromagnets—and the control or selective actuation of the moving means, from a remote point if desired, through simple and improved switch and conductor means. In a preferred embodiment of the invention the control switch means is movable at will between two positions, and by very simple arrangements the movable system is moved between a respective two positions in accordance with the movement of the switch means.

It is an object of the invention to provide a novel and simple control of the type described.

It is an object to provide an improved control of that type employing a minimum number of conductors between the control means and the movable system.

It is an object to provide simple means whereby the movable system will be kept in step with the control means with a high degree of reliability.

It is an object to provide simple means whereby the movable system, if out of step, will be promptly and automatically restored to step with the control means.

It is an object to provide an improved control wherein the actuating currents for movement of the movable system in a plurality of directions are conveyed thereto from the control means through the same conductor.

It is an object, in such a control, to render the movable system selectively responsive to the different control means movements with a high degree of reliability.

It is an object, in such a control, to provide improved means for preventing multiple operation of the movable system upon single manipulations of the control means.

It is an object to provide a novel arrangement of electromagnetic device and system moved thereby only upon lower-power actuation of that device.

Other and allied objects will more fully appear from the following description and the appended claims.

In the description reference is had to the accompanying drawing, of which

Figure 1 is a schematic diagram of a control embodying our invention in one form; and

Figure 2 is a schematic diagram of a portion of

a control embodying our invention in a modified form, Figure 2 being intended for optional substitution for the righthand portion of Figure 1.

In the illustration of our invention we have shown a movable system comprising a lever 1, pivoted as at 1' and rockable for example from the illustrated inclined position to a position correspondingly inclined on the other side of vertical. Any other device whose control between two positions is to be effected may be connected to the lever 1, thus entering into the movable system; this has been schematically indicated by the device 4 having the control lever 3, and the rod 2 terminally pivotally connected with and coupling together the levers 3 and 1. Purely as an example, the device 4 may be a clutch or other apparatus, moved between engaged and disengaged positions by the movement of the lever 1.

For moving the lever 1 between its two positions there has been illustrated an assembly of two electromagnets 11 and 12, alternately actuatable to effect alternately directed lever movements. While the response of the lever to the electromagnets may be a direct one, we prefer that this response take place through the intermediary of a double pivoted armature arrangement, following the teachings of U. S. Patent No. 1,380,486, issued June 7, 1921, on application of Sam G. Langley. While the armature arrangement may follow as closely as desired the arrangement shown in that patent, we have illustrated it in simple form as comprising a pair of armatures 13 and 14 pivoted at and extending upwardly from points 13' and 14' on either side of the lever-pivoting point 1', and a spring 17 tensioned between the armatures to bias them against the respective sides of an enlarged head 1a provided at the top of lever 1. The electromagnets 11 and 12 may be positioned respectively to the right and left of intermediate portions of the armatures 13 and 14, the electromagnet axes lying for example in a common horizontal line. The components may be arranged so that when (as illustrated) armature 13 touches the pole tip 11' of electromagnet 11, that armature will be substantially vertical, lever 1 will be in its "first" position (of rightward-upward inclination), and armature 14 will have a rightward-upward inclination and will be spaced from the pole tip 12' of electromagnet 12—whereas when armature 14 has been attracted to touch pole tip 12', that armature will be substantially vertical, lever 1 will have been moved to its "second" position (of leftward-upward inclination), and armature 13

will have a leftward-upward inclination and will be spaced from pole tip 11'.

It may be desirable to positively maintain the movable system in either of its two positions until the deliberate movement thereof to the other position by electromagnet actuation. While any means may be employed for this function, there is very appropriate with the illustrated armature arrangement a means similar to that disclosed in the mentioned Langley patent. This may comprise a pair of cams 15 and 16, each cam being secured to a respective one of the armatures 13 and 14, somewhat above the point of pivoting of the latter, and extending toward the other armature. The top surface of each cam (e. g., 16') may be arcuate about the pivot point (e. g., 14') of the armature to which that cam is connected; the outer end surface of each cam (e. g., 15'') may also be arcuate and, when the armature to which that cam is connected is vertical (i. e., in substantial contact with the respective pole tip), that end surface may be in substantial contact with the top surface (e. g., 16') of the opposite cam. It will be obvious that the top of the cam connected with the inclined armature acts as a stop for the end of the cam connected with the vertical armature, and hence as a lock to maintain the latter armature in its vertical position; this lock for the vertical armature, together with the spring 17 effective on the inclined armature, positively maintains the movable system in that one of its two positions which it has assumed, until the deliberate movement of the inclined armature. It will further be understood that when the inclined armature (e. g., 14) is subjected to movement toward its vertical position, the respective top cam surface (e. g., 16') will slide along the end surface (e. g., 15'') of the opposite cam, clearing that end surface only when that movement is substantially completed; only upon that clearing will the originally vertical armature (e. g., 13) be effectively unlocked, whereupon it will execute a "follow-up" movement to its inclined position under the influence of spring 17. In the absence of some constant bias (for example, from the device 4) causing it to follow the first-moved armature, the lever 1 will be moved from its original to its opposite position by the "follow-up" movement of the originally vertical armature.

A current source 20 is illustrated, one terminal of the source being connected to a control switch S hereinafter described, as through a conductor 21. The other terminal of the source 20 is connected to the control switch S through the conductor 22, in which the electromagnet assembly is serially connected to be controllably supplied with current; in other words, the conductor 22 may be considered as broken, and the ends produced by the break respectively connected to terminals A and B of the electromagnet assembly. First terminals of the respective electromagnets may be connected together to form the assembly terminal A. The other terminal B of the assembly may comprise the pole of a switch means which is automatically operated by each electromagnet, upon actuation of that electromagnet, to disconnect the conductor 22 from the actuated electromagnet and to connect it to the other electromagnet. A switch means to perform a similar immediate function was disclosed in the mentioned patent to Langley, to which reference may be had if desired for one typical construction; in the instant case the switch means may be very simply provided by employ-

ing a portion of the lever 1 as a switch pole (the terminal B being specifically, for example, formed at the pivoting point 1'), and by arranging two contacts 10 and 9 to be respectively contacted by that switch pole when the lever 1 is respectively in its first and second positions. Contact 9 is electrically connected to the second terminal of electromagnet 11, contact 10 to the second terminal of electromagnet 12.

10 In general, this arrangement may be considered as a means, included in the electromagnet assembly, for alternating the supply of current to the two electromagnets.

15 Thus with the lever 1 disposed in its first (illustrated) position, the electromagnet 12 is the one which will be actuated on the next current supply through conductor 22. Upon that supply and actuation the armature 14 will be sharply accelerated toward pole tip 12', and the 20 lever 1 and armature 13 will follow it in manner already described. The lever movement will disconnect the conductor 22 from the electromagnet 12 at contact 10, and will connect that conductor to the electromagnet 11 at contact 9. 25 The electromagnet 11 has then become the one which will be actuated upon further current supply through the conductor 22.

30 In the mentioned patent to Langley separate conductors were employed to lead actuating current to the respective electromagnets. The control switch was a simple single-pole, double-throw switch which operated to keep voltage continuously supplied to one or the other of these conductors, according to its throw; the switch 35 means automatically operated by the electromagnets was relied on to limit the electromagnet actuations to single, momentary ones. With the instant control system, however, only one conductor is employed for the actuation of both 40 electromagnets; and it will be obvious that, unless some special measure be taken, operation of the control switch to keep voltage continuously supplied to the single conductor would result in a sustained oscillation of the movable 45 system back and forth between its two positions. In other words, although the automatically operated switch means still functions to limit actuations to momentary ones, it no longer in itself can function to limit the actuations to single 50 ones.

55 We may limit the actuations to single ones by employing for the control switch S a switch which in each throw executes only a temporary closure, for an interval which is automatically ended before the lever 1 has contacted the contact (10 or 9) to which it is being thrown by that closure. Such a switch has been schematically illustrated in Figure 1. It may comprise simply a switch pole 31 pivoted as at point 31', throwable back and forth in an arc (for example below point 31') between two stationary stop members 33, and passing over and contacting a stationary contact 30 in each of its throws. The switch pole 31 is thrown in a uniform manner 60 by a toggle arrangement comprising an arm 35 pivoted for example at the same point 31' but extending therefrom to be thrown in a somewhat larger arc, on the opposite side of (e. g., above) point 31', between stationary stop members 36; pole 31 may be toggled to arm 35 as by spring 65 34 tensioned between pins 31a and 35a extending forwardly from intermediate points on pole and arm, respectively. Arm 35 may be thrown directly or in any convenient manner. By way 70 of example there has been shown a rod 37 piv-

otally secured to the arm and passing leftwardly therefrom through an aperture 38' in panel 38, to terminate in a knob 40 which may be pushed and pulled toward and away from the panel to throw the arm; the arm may be subjected only to the bias of the toggle spring 34 urging it to retain each of its two positions, or if desired may be biased into a predetermined one of those positions by a sufficiently strong spring 39. However it is chosen to throw arm 35, it will be understood that as the arm, in a leftward throw from its illustrated or "first" position of contact with the rear stop member 36, closely approaches the front stop member 36, the spring 34 will pass across the pivoting point 31' and will thereupon cause the forward throw of pole 31, with momentary closure of that pole against contact 39. A converse but entirely analogous action takes place on rightward throw of arm 35. The duration of the contact of 31 with 39, or interval of control switch closure, on each throw may be predetermined at desired value by apportionment of the length of the contact 39 in the direction of the throw, the tension of spring 34, and the effective mass of pole 31—the latter being regulable as by suitable weighting of its extremity, indicated as 32.

The control switch S as so described may be connected to by the conductor 21 at 39; and by the conductor 22 at 31', through the schematically indicated switch 23 which at the moment may be taken as closed to short-circuit and functionally eliminate the elements shown above the arm 35. Its function may be considered to be the supply to the electromagnet assembly of current pulsations, each pulsation for a single actuation of one of the electromagnets and consequent single throw or movement of the movable system; and under theoretically perfect conditions the control switch and movable system will remain in step, or predetermined positional relationship, with each other. Possibilities exist, however, of various influences occasionally causing an abnormally long switch closure, with double or other multiple electromagnet actuation; and for many purposes there cannot be tolerated even the small degree of independability which these possibilities entail. It is also of course possible in very exceptional cases that a closure of the control switch will be deficient to such a degree that no electromagnet actuation takes place thereon, a reversal of proper relationship thus being caused; or, again, that a reversal may have been effected by some ill-advised, purely mechanical manipulation of one of the parts.

Our invention accordingly contemplates a plurality of arrangements for constraining the electromagnet assembly to move the movable system in predetermined directional relationship to the movement of the control switch, or constraining the movable system to a predetermined positional relationship with the switch. Thus a function of each arrangement is to automatically restore the system and switch, if at any time they are out of step, into step. Two of these arrangements are incorporated in the control of Figure 1; each operates on the throw of the control switch in one of its directions to prevent the operation of that electromagnet whose operation on that throw is improper. Each involves a differentiation between the current pulsations or currents respectively supplied on the two throws of the control switch; this differentiation may be simply a differentiation of the voltages at which the currents are supplied, effected for example by the 75

selective inclusion in circuit of a resistance. When such a resistance is employed it is usually most conveniently provided in physical adjacency to the switch S; but wherever physically located it, or whatever differentiating means is employed, may be considered as forming a part of the control means.

To associate a resistance with the control switch S so that it functions to limit the voltage 10 on one but not on the other throw, we may expand the control switch to a form such as described and claimed in the co-pending application of the present co-applicant Richard M. Somers, Serial No. 252,523, filed January 24, 1939. 15 Typically this may be done by employing the abovementioned arm 35 as a switch pole, with a contact button 35a carried in its right-angularly twisted upper end portion 35b; and by arranging two contact springs 41 and 42, with respective 20 contact points 41a and 42a, adapted to be contacted by the arm (e. g., by button 35a) when the arm is respectively in its first and second positions. Conductor 22 may be connected to spring 41 directly, and to spring 42 through the 25 resistance 25 bridged between the springs; arm 35 is of course electrically connected to pole 31, as at the common pivot point 31'. The schematically illustrated switch 23 will of course be kept open to render the springs 41 and 42 and arm 35 effective to control the connection of conductor 22 with pole 31.

The springs are arranged so that as arm 35 is moved toward either spring, that spring will be contacted by the arm materially before the arm 35 reaches the extremity of its movement in that direction, the spring flexing as that movement is completed. Accordingly as the arm 35 is moved leftwardly from its first (illustrated) position to its second position, it will quit contact with spring 41 and make contact with spring 42, and only after the contact with spring 42 is established will the arm cause the forward throw of the pole 31; thus in this throw of the control switch conductor 22 is supplied with a current pulsation 40 from conductor 21 through the voltage-limiting resistance 25. Conversely, as the arm 35 is moved from its second position to its first position, it will quit contact with spring 42 and make contact with spring 41, and only after the latter contact is made will the arm cause the rearward throw of pole 31; thus in this throw of the control switch the conductor 22 is supplied with a current pulsation free of voltage limitation by the resistance 25.

55 One of the constraining arrangements incorporated in Figure 1 is a means associated with the electromagnet 12—which is the electromagnet intendedly actuated, to throw the movable system to its second position, by the limited-voltage current supplied on throw of the control switch S to its second position—for preventing its operation of throwing the movable system to second position when full-voltage current is supplied to it. While there may be employed any of a variety of means for preventing the electromagnet operation under these conditions, we have illustrated a means which, though it permits the actuation of the electromagnet (i. e., its energization in sufficient degree to move its armature, in the absence of abnormal armature restraint), renders that actuation ineffective by blocking the response of the movable system thereto. In turn, while the means for blocking the response of the movable system may be associated with that system in any of a variety of manners, we have il-

lustrated it as a means which immediately influences the armature 14.

Thus at the end of the electromagnet 12 opposite to its armature end there may be provided a catch member 50, having a top extremity pivoted as at point 50', extending generally downwardly therefrom past the pole tip 12'' at this end of the electromagnet to below the electromagnet, and having a small lug portion 50a formed rightwardly from its lower extremity. The catch member 50 may be of very light material and structure, but opposite the pole tip 12'' it may carry a small armature 51 of magnetic material adapted for attraction by that pole tip. The catch member 50 may be biased leftwardly against a stop member 52 as by a tension spring 53; when the catch member is in its rest position of contact with this stop member, the armature 51 may be slightly spaced from the pole tip 12''. Rigidly secured to armature 14 and extending therefrom leftwardly underneath the electromagnet 12 is an arm 55. This arm is of such length that as the armature 14 is rocked when the catch member 50 is in rest position, the left-hand arm extremity will just clear the lug portion 50a. The bottom of the arm extremity may be spacedly above the level of the top of lug portion 50a when the armature 14 is rightwardly inclined (as illustrated), but may move to slightly below that level as the armature 14 is attracted into contact with pole tip 12'.

The spring 53 is made just dependably strong enough to prevent the attraction of the catch member 50 by the electromagnet 12 when the latter is actuated by the limited-voltage current supplied upon throw of the control switch to its second position; accordingly the then-intended throwing of the movable system to its second position is not interfered with. Should the full-voltage current be supplied to the electromagnet 12, however—either by reason of the apparatus having previously gotten out of step, or by reason of a closure of the control switch S, on its throw to first position, continuing until after the throw of the movable system—the armature 51 will be attracted to the pole tip 12'', and the lug portion 50a of the catch member will be brought under the extremity of the arm 55. In view of the spacing factors detailed above, the lug portion 50a will prevent at least the final small portion of downward movement of arm 55 and leftward movement of armature 14; and since the cams 15 and 16 act to prevent movement of the vertical armature until that of the inclined armature is substantially completed, the armature 13 will be maintained stationary no matter how long the full-voltage current supply may continue. At the termination of that supply, the springs 17 and 53 will of course cause the armature 13 and the catch member to resume their illustrated positions, the operation of the electromagnet 12 to throw the movable system having been thus prevented.

It will be understood that the catch member 50, which is not movable by the limited-voltage current supply to electromagnet 12, must by the full-voltage current supply to that electromagnet be moved so rapidly that its lug portion 50a dependably moves into the path of the end portion of arm 55 before the armature 14 movement is completed—this in spite of the fact that the armature 14, since it must be dependably movable by the limited-voltage current supply to electromagnet 12, will be quite rapidly accelerated by the full-voltage current supply. The

very small effective mass of the catch member 50 relative to the large effective mass of the armature 14 with arm 55 is, however, sufficient to insure the proper action, particularly since advantage is taken of the ability to block the movement of the movable system by blocking only a small terminal portion of the armature 14 movement—an ability arising from the action of the cams 15 and 16. It may be noted that if the device 4 tends to impart any bias to the lever 1, toward one or the other armature, it is desirable that it be toward the armature (e. g., 13) opposite to that with which a preventing structure of the particular type illustrated is associated.

15 The constraining arrangement so described prevents operation of one of the electromagnets (e. g., 12, intended to be actuated by the limited-voltage current) by the current (e. g., of full voltage) not intended for that electromagnet; it 20 accordingly permits any continued length of control switch closure in the throw intended to actuate the other electromagnet (e. g., 11); and it restores to normal the positional relationship between the movable system and the control switch, 25 if that has by any mishap been reversed, either upon the first control switch closure succeeding the reversal (if immediately succeeding the reversal electromagnet 12 is prepared for actuation) or upon the second control switch closure 30 succeeding the reversal (if immediately succeeding the reversal electromagnet 11 is prepared for actuation)—in any event within one cycle of operation of the control switch.

The other constraining arrangement incorporated in Figure 1 also depends upon differentiation between the alternate current supplies, as by the means already described, but does not involve the use of the catch member 50, arm 55 etc. of the first arrangement; it may be considered initially with the latter elements omitted from the control. Its ultimate functions are analogous but converse to those set forth, for the first-described arrangement, in the last preceding paragraph—that paragraph applying literally to the second arrangement if read with electromagnet 11 substituted for electromagnet 12 and vice versa, and with full-voltage current substituted for limited-voltage current and vice versa. The second arrangement consists simply in the arrangement of electromagnet 11 so that it is actuatable only by current at a voltage substantially exceeding the limited voltage abovementioned—e. g., is actuatable by the full-voltage current—while electromagnet 12 remains actuatable (i. e., capable of being energized in sufficient degree to move its armature) by either the full-voltage or limited-voltage current. Purely as an example of a means for rendering the electromagnet 11 actuatable only as stated, there has been illustrated in series with it in the electromagnet assembly a resistance 19; but it will be understood that the means may consist in any element or elements in or associated with the electromagnet, such as the electromagnet coil itself (11c), then wound for ineffectiveness when supplied with current at only the limited voltage.

The performance of the ultimate functions abovementioned will be understood to follow inherently from the ineffectiveness of the supply to electromagnet 11 of the limited-voltage current. In general, it may be said that this constraining arrangement operates electrically and, in distinction thereto, that the first-described one operates mechanically.

While either of these constraining arrange-

ments may be employed without the other, for the benefits already made apparent, we prefer to employ them in combination with each other. Such a combination prevents operation of each of the electromagnets by the current at a voltage respectively not intended for that electromagnet; it accordingly permits any continued length of control switch closure in each of the two throws of that switch, so that the apparatus may be considered to be effectively maintained, rather than merely constrained, in step. And in the highly exceptional case of failure of switch closure on switch throw, or of mechanically effected reversal of the proper relationship, the combination restores the proper relationship between control switch and movable system upon the very first control switch closure following the reversal, so that its residual constraining function is especially efficiently performed.

It will of course be understood that while the duration of each current pulsation need no longer be limited for the purpose of avoiding multiple electromagnet actuation, it is generally desirable that the current supply shall still take place in the form of pulsations as distinguished from indefinitely continued supplies, for the avoidance of unnecessary and wasteful continued current flow, overheating of the electromagnets, etc. The system may if desired, however, be operated with spring 34 removed and switch pole 31 left in contact with contact 30 (the "first" and "second" positions of the arm 35 and knob 48 in such a case becoming the opposites of those above described). It is therefore to be understood that we do not intend to limit all aspects of our invention to the supply by the control switch of momentary currents.

In Figure 2 we illustrate a modification of the electromagnet assembly (operable for example with a control switch S similar to that illustrated and described for Figure 1), in which the second constraining arrangement above described may again be employed; but with it there is employed, instead of the first constraining arrangement, a modified arrangement with a somewhat different immediate function. As will hereinafter be apparent, this in itself functions to avoid multiple electromagnet actuation on the supply of current to one of the electromagnets by retarding the completion of operation of that electromagnet; employed, as illustrated, in connection with the second constraining arrangement, it provides a composite system whose overall function is almost identical with that of Figure 1. The changes in the electromagnet assembly lie in the omission of the catch member 50, arm 55 etc. from association with electromagnet 12; and in the association with electromagnet 11 (that actuatable only by the larger current) of a somewhat analogous structure—but with the arm therein still associated with the same armature as in Figure 1, which is to say armature 14 for the electromagnet 12 actuatable by the current at either voltage.

Thus at the end of the electromagnet 11 opposite to its armature end there may be provided a catch member 60, having a bottom extremity pivoted as at point 60', extending generally upwardly therefrom past the pole tip 11" at this end of the electromagnet to above the electromagnet, and having a small lug portion 60a formed leftwardly from its upper extremity. The catch member 60 may be of very light material and structure, but opposite the pole tip 11" it may carry a small armature 61 of magnetic ma-

5 terial adapted for attraction by the pole tip. The catch member 60 may be biased rightwardly against a stop member 62 as by a tension spring 63; when the catch member is in its rest position of contact with this stop member, the armature 61 may be slightly spaced from the pole tip 11". Rigidly secured to the top of armature 14, and extending therefrom rightwardly above the armature 13 and the electromagnet 11, is an arm 65. This arm is of such length that as the armature 14 is rocked when the catch member 60 is in rest position, the righthand extremity of the arm will just clear the lug portion 60a. The bottom of the arm extremity may be slightly spaced above the level of the top of lug portion 60a when the armature 14 is vertical (as it has been illustrated in this figure), but may move to below that level as the armature 14 executes a follow-up movement rightwardly after attraction of armature 13 into contact with pole tip 11' on actuation of the electromagnet 11.

Whenever the electromagnet 11 is actuated, the catch member 60 will be attracted leftwardly by pole tip 11", and lug portion 60a will come into the downward path which the extremity of arm 65 has to traverse during the follow-up movement of armature 14. All but a very small initial portion of that follow-up movement is accordingly prevented so long as the current supply through conductor 22 continues; with it there is correspondingly prevented any significant movement of the lever 1 and movable system (any bias of the upper portion of lever 1, as by the device 4, now being preferably a leftward one). It will be understood that the slight initial movement of armature 14 which is permitted serves to permit the top surface of cam 16 to get underneath the end surface of cam 15, so that when the current supply ceases and catch member 60 is withdrawn rightwardly, the follow-up movement of armature 14 will dependably occur. It will also be understood that, by virtue of cams 15 and 16, no movement of the arm 14 will tend to occur upon actuation of the electromagnet 11 until after the movement of arm 13 has been substantially completed; thus there is an especially wide safety margin of time interval in which the light catch member 60 may be attracted into its interfering position.

There may be reviewed the action of the control of Figure 2 under conditions of current supplies from the control switch not themselves sufficiently short to avoid multiple electromagnet actuation. The operation of the catch 60 prevents multiple electromagnet operation upon the intended supply to electromagnet 11 of the full-voltage current—by preventing the transfer of current supply to the electromagnet 12 at contact 10 so long as the supply continues. The ineffectiveness of the limited-voltage current on electromagnet 11 of course prevents multiple operation on the intended supply to electromagnet 12 of that current; it also of course prevents any operation at all on an unintended supply to electromagnet 11 of that current, so restoring the movable system to step with the control means as it did under similar conditions in the control of Figure 1. In the one case of an unintended supply to electromagnet 12 of the full-voltage current can a multiple operation occur—and that multiple operation will be limited to a double one, also effective to restore the movable system to step with the control means. And of course if the current supply from the control means is sufficiently short to avoid multiple operation,

any out-of-step condition will be automatically rectified on the first supply to electromagnet 11 of the limited-voltage current—necessarily within the first cycle of control switch operation following the displacement from normal relationship.

It will be understood that while we have shown and described our invention in terms of two particular embodiments thereof, these embodiments are presented in an illustrative rather than in a limiting sense. Thus for example the electromagnetic assembly may comprise any of a variety of forms of electromagnetic devices or the control means may comprise switch means of any of a variety of forms, adapted to perform functions analogous to those above indicated as expected of those respective elements. Modifications in these or other respects from the details of the illustrated embodiments will readily suggest themselves to those skilled in the art, and will not necessarily constitute departures from the true spirit and proper scope of the invention.

We claim:

1. In an electrical control system including means operable to supply currents at two different voltages through a common conductor: the combination of an electromagnetic assembly supplied with said currents, said assembly comprising a pair of electromagnetic devices and means for alternating the supply of current thereto; a movable system electromagnetically operated between respective positions by said devices; and means, comprised in said assembly, for rendering each of said devices ineffective to operate said system when supplied with current at a respective one of said two voltages.

2. In an electrical control system including means operable to supply currents at two different voltages through a common conductor: the combination of an electromagnetic assembly supplied with said currents, said assembly comprising a pair of electromagnetic devices and means for alternating the supply of current thereto; a system movable by said devices; and means, operated by one of said devices when current at a predetermined one of said voltages is supplied thereto, for blocking the movement of said system by that device.

3. In an electrical control system including means operable to supply currents at two different voltages through a common conductor: the combination of an electromagnetic assembly supplied with said currents, said assembly comprising an electromagnetic device actuatable by current at the larger only of said voltages, an electromagnetic device actuatable by current at either of said voltages, and means operated by said devices for alternating the supply of current thereto; a movable system operated by said devices; and means, comprised in said assembly, for preventing operation of said second-mentioned device by the supply of said larger-voltage current continued after actuation of said first-mentioned device.

4. In an electrical control system including means operable to supply currents at two different voltages through a common conductor: the combination of an electromagnetic assembly supplied with said currents, said assembly comprising an electromagnetic device actuatable by current at the larger only of said voltages, an electromagnetic device actuatable by current at either of said voltages, and means operated by said devices for alternating the supply of current there-

to; a movable system operated by said devices; and means, comprised in said assembly and rendered effective throughout the supply of said larger-voltage current to said first-mentioned device, for preventing the transfer of current supply to said second-mentioned device.

5. In an electrical control system including means operable to supply currents at two different voltages through a common conductor: the combination of an electromagnetic assembly supplied with said currents, said assembly comprising an electromagnetic device actuatable by current at the larger only of said voltages and an electromagnetic device actuatable by current at either of said voltages; a movable system electromagnetically operated between respective positions by said devices; and means, associated with said second-mentioned device, for preventing the operation of said system thereby upon actuation of that device with said larger-voltage current.

6. The combination according to claim 5, wherein said assembly further comprises means operated by the devices for alternating the supply of current to said two devices.

7. In an electrical control system including means operable to supply currents at two different voltages through a common conductor: the combination of an electromagnetic assembly supplied with said currents, said assembly comprising a pair of electromagnetic devices; a movable system electromagnetically operated between respective positions by said devices; means for electrically rendering one of said devices ineffective to operate said system upon supply to that device of current at one of said voltages; and means for mechanically rendering the other of said devices ineffective to operate said system upon the supply to that device of current at the other of said voltages.

8. The combination according to claim 7, wherein said assembly further comprises means operated by the devices for alternating the supply of current to said two devices.

9. In an electrical control system including means operable to supply currents at two different voltages through a common conductor: the combination of an electromagnetic assembly supplied with said currents, said assembly comprising a pair of electromagnetic devices; a movable system electromagnetically moved between respective positions by said devices; and means, comprised in said assembly, for causing each of said devices to operate said system only in response to current at a respective one of said two voltages.

10. The combination according to claim 9, wherein said assembly further comprises means operated by the devices for alternating the supply of current to said two devices.

11. In an electrical control system including control means throwable between two positions to supply on its respective throws currents at two different voltages through a common conductor: the combination of an electromagnetic assembly supplied with said currents; a movable system electromagnetically moved in respective directions between two positions by said assembly; and means, comprising voltage-controlled means in said assembly, for constraining said assembly to move said system in predetermined directional relationship to the movement of said control means.

12. The combination according to claim 11, wherein said assembly comprises a pair of elec-

tromagnetic devices and means operated by the devices for alternating the supply of current thereto.

13. In an electrical control system including control means throwable between two positions to supply on its respective throws currents at two different voltages through a common conductor: the combination of an electromagnetic assembly supplied with said currents; a movable system electromagnetically moved in respective directions between two positions by said assembly; and means, including voltage-controlled means in said assembly, and rendered effective upon an operation of said control means following any departure of said system from predetermined positional relationship with said control means, for restoring said system to that predetermined relationship.

14. The combination according to claim 13, wherein said assembly comprises a pair of electromagnetic devices and means operated by the devices for alternating the supply of current thereto.

15. In an electrical control system including means operable to supply currents at two different voltages: the combination of an electromagnetic device supplied with said currents; a movable system electromagnetically moved by said device upon the supply to said device of current at the smaller of said voltages; and movable means, moved by said device upon the supply to said device of current at the larger only of said voltages, for interfering with the movement of said system by said device upon said supply of larger-voltage current.

16. In an electrical control system including means operable to supply currents at two different voltages: the combination of an electromagnetic device supplied with said currents; a system electromagnetically moved by said device

upon the supply to said device of current at the smaller of said voltages; and means, associated with said device and rendered effective by the supply to said device of current at the larger only of said voltages, for rendering said device ineffective to move said system upon said supply of larger-voltage current.

17. In an electrical control system including means operable to supply currents at two different voltages: the combination of an electromagnetic device supplied with said currents; an armature subjected to movement by said device upon the supply to said device of current at the smaller of said voltages; a movable system mechanically moved by, but only at the substantial completion of, said armature movement; and means, associated with said device and rendered effective by the supply to said device of current at the larger only of said voltages, for blocking the terminal portion of said armature movement, whereby to prevent movement of said movable system upon said larger-voltage current supply.

18. In an electrical control system including means operable to supply currents at two different voltages: the combination of an electromagnetic device supplied with said currents; an armature subjected to movement by said device upon the supply to said device of current at the smaller of said voltages; a movable system mechanically moved by, but only at the substantial completion of, said armature movement; and a member of small effective mass relative to that of said armature, arranged for movement by said device upon the supply of current thereto but biased against movement upon said smaller-voltage current supply, moved upon said larger-voltage current supply into position interfering with said armature movement.
